PAGE 2

FIG. 2

FIG. 3

FIG. 4

FIG. 5

FIG. 6

FIG. 1 is a front perspective view of a document reader showing our new design;

FIG. 2 is a top plan view thereof;

FIG. 3 is a front elevational view thereof, the hopper being broken away for convenience of illustration;

FIG. 4 is a rear elevational view thereof;

FIG. 5 is a right side elevational view thereof; and

FIG. 6 is a left side elevational view thereof.

We claim:

The ornamental design for a document reader, as shown.
